Primary Examiner—Catherine Tuttle(74) *Attorney, Agent, or Firm*—Steptoe & Johnson LLP(57) **CLAIM**

The ornamental design for an accordion-folded container, as shown and described.

DESCRIPTION

FIG. 1 is a front view of an accordion-folded container embodying the ornamental design;

FIG. 2 is a back view of the container of FIG. 1;

FIG. 3 is a left side view of the container of FIG. 1;

FIG. 4 is a right side view of the container of FIG. 1;

FIG. 5 is a top or plan view of the container of FIG. 1;

FIG. 6 is a bottom view of the container of FIG. 1; and,

FIG. 7 is a cross-sectional view of the container of FIG. 1, along plane VII—VII indicated in FIG. 1.
